UNITED STATES PATENT OFFICE.

LEWIS H. PFLEGHARDT, OF FAYETTE CITY, PENNSYLVANIA.

CURTAIN-POLE.

No. 867,750.

Specification of Letters Patent.

Patented Oct. 8, 1907.

Application filed August 3, 1906. Serial No. 329,036.

To all whom it may concern:

Be it known that I, LEWIS H. PFLEGHARDT, a citizen of the United States of America, residing at Fayette City, in the county of Fayette and State of Pennsylvania, have invented certain new and useful Improvements in Curtain-Poles, of which the following is a specification, reference being had therein to the accompanying drawing.

This invention relates to curtain poles, and its object 10 is to provide a simple and inexpensive device of this character whereby curtains may be supported without the use of the usual suspending rings and pins.

The invention comprises a curtain pole consisting of two separable sections provided with novel means for 15 detachably connecting said sections together, and for securing the curtains between the sections.

The construction of the improvement will be fully described hereinafter in connection with the accompanying drawing and its novel features will be defined in 20 the appended claims.

In the drawing, Figure 1 is a front elevation of a curtain pole embodying the invention, Fig. 2 is a top plan view of the same, Fig. 3 is a top plan of one section of the pole, Fig. 4 is an elevation of the inner side of the other 25 section, and Fig. 5 is a transverse vertical section of the pole.

The pole consists of two sections designated respectively by the reference numerals 1 and 2, each of which is preferably of semi-circular form in cross section.

30 The section 1 is provided with a series of pins 3 projecting from its inner flat face in horizontal alinement and the other pole section 2 is formed with openings 4, so spaced apart as to register with the pins 3 which project into said openings. Each of the two pole sections is 35 provided at its upper side near one end with a lug 5, thus providing a lug at each end of the completed pole when the sections are connected.

Before the two sections are put together the curtains are hung upon the pins 3, after which the section 2 is 40 placed upon the section 1, the pins fitting into the openings 4 as above stated. To secure the sections together I provide end caps or ferrules 6 each formed with a bayonet slot 7, said slots being oppositely disposed as shown. These securing caps or ferrules afford a simple 45 convenient, and effective means for detachably connecting the pole sections, and the device as a whole provides a very simple and attractive curtain support which may be manufactured at small expense.

As shown, the pins 3 are simply small nails driven 50 through the section 1 and into the section 2, thereby providing, when the sections are separated, the projecting portion of the pin and the corresponding opening in the opposing section. No particular care need be taken in positioning the pins along the section, since

the sections, being separable only in a direction corresponding with the longitudinal axis of the pins, require no enlarging of the openings to receive the pins, such as would be required were the separation other than in a direction which will preserve the parallel relationship of the faces of the sections as long as the pins remain within the openings. As the lugs are readily placed in position, and the end caps are readily formed, it will be obvious that the structure is one which is extremely simple, of low cost of manufacture and durable. And should it be found, in use, that sufficient pins are not initially provided, it is necessary only to drive additional nails through section 1 without requiring the removal of the sections such as would be required to prepare or enlarge the opening to receive it. And obviously, the same course can be pursued in case the projecting ends of the pins should become broken off should it not be desired to take the time to remove the remaining portion of the pin. In addition, the location of the lugs on opposite sections when used in connection with end caps in which the bayonet slots have 7 their lateral recesses extending in opposite directions when applied to the opposite ends of the pole, causes the operator to move the caps in opposite directions when binding the sections together and insuring a close fitting of the sections so that the opposing faces of the 80 sections aid in supporting the curtain in position.

What I claim and desire to secure by Letters Patent, is:—

1. A curtain pole comprising two semi-circular sections having co-operating pins and openings located respectively in the two sections, each section having a flat face, said faces opposing and lying parallel with each other, and separable only in a direction corresponding with the longitudinal axis of the pins to preserve the parallel relationship of the faces, lugs carried by the sections adjacent the ends thereof, and end-caps having bayonet slots to receive the lugs. 85

2. A curtain pole comprising two equal semi-circular half sections, one provided longitudinally of its flat face with a series of openings, pins passed entirely through the other section and projecting beyond the flat face thereof and adapted to be received in said openings, said sections having their faces lying parallel with each other and separable only in a direction corresponding with the longitudinal axis of the pins to preserve the parallel relationship of the faces, a lug projecting from each section near the end thereof, the lug of one section being at the end opposite to the lug on the other section, and end caps for said section having bayonet slots to receive said lugs, said slots having their lateral recesses extending in opposite directions, substantially as shown and described. 90 100 105

In testimony whereof I affix my signature in the presence of two witnesses.

LEWIS H. PFLEGHARDT.
